UNITED STATES PATENT OFFICE.

ALVA J. FISHER, OF EVANSTON, ILLINOIS.

SPLINE-CARRYING-MACHINE ELEMENT.

1,391,728.

Specification of Letters Patent. Patented Sept. 27, 1921.

Original application filed December 23, 1918. Serial No. 267,991. Divided and this application filed February 16, 1920. Serial No. 358,953.

To all whom it may concern:

Be it known that I, ALVA J. FISHER, a citizen of the United States, residing at Evanston, in the county of Cook and State of Illinois, have invented certain new and useful Improvements in Spline-Carrying-Machine Elements, of which the following is a specification.

Machine elements that are to be splined to shafts are usually made of steel, machined to provide the shaft receptive hole and the spline slot, and into said slot the separately-made spline must be accurately fitted, either with a drive fit or with provisions for rivet-retention. Inherently these elements are relatively expensive, even in quantity production. Generically such splined elements must be accurate in shaft-hole size and centering, in the location, extent of projection 20 and size of the spline, and in firm anchorage of the spline in the element-body. Of course these machine-elements may take an unlimited number of external forms, sizes, and designs, and in a great number of instances the 25 element to be produced is of a character that might well have its body made of cast metal if the requirements as to the shaft-hole and the spline can be met in the cast article.

My invention is intended to provide an inexpensive satisfactory construction of spline-carrying machine-element having its body a casting, and adapted to be made by the economical process and by means of the simple apparatus set forth in my copending application Serial No. 267,991, filed December 23, 1918, of which this is a division.

As a single instance, for purposes of disclosure, I have selected a splined clutch-element as the subject of illustration, (but 40 without intent, of course, to limit my invention in its broader aspects to such specific article), and in the drawings, Figure 1 is a perspective view, with parts broken away, showing the splined clutch element with a 45 cast-metal body; Fig. 2 is a perspective detail of a sleeve or liner; Fig. 3 is a perspective detail of a spline-member detached, and Fig. 4 is a section of a mold with a core and other parts assembled therein ready for the 50 casting of the element-body.

In detail the particular element illustrated in Fig. 1 is a clutch member 10 adapted for sliding fit with a grooved shaft, and the body 11 of the member is shown as 55 a casting shaped to provide end heads 12

and an intervening reduced waist 13, each head having crown teeth or projections 14. The shaft hole 15 extends axially through the body and is faced with a liner 16, pre-formed to its cylindrical contour of specified 60 diameter. Through a slot 17 in this liner and into the shaft hole 15 there projects a spline-member 18, partly embedded in the body-casting, and co-operating with the liner and the cast body so that the several parts 65 mentioned are united with substantially the rigidity and permanency of an integral structure.

For the production of the specific article thus illustrated one preferably employs a 70 usual casting flask 20, having a suitable sand-cavity, and a special core element 22 congruent, in part, with the pattern and designed for co-operation with the sleeve 16 and spline 18 during the casting operation. 75 This core element is so constructed that it may be removed subsequently to the completion of the casting. The core-element 22 has heads 24 and 24' preferably of metal to constitute chill blocks, and these heads fit in 80 the guide portions of the cavity, as shown in Fig. 4. In the simple element shown these two heads may be duplicates in external shape, and provided with confronting recesses 25 to give form to the clutch teeth 14 85 of the machine-element. One head 24 is axially removable from the core stem 26 that connects them, such head fitting snugly on a reduced stem-extension 27 in the end of which there is a chord-notch to engage a 90 transverse pin 29 insuring that the removable head always goes on the core-stem in the same position with its notches 25 in proper register with, or in desired angular relation to, the notches in the opposed fixed 95 head 24'. The stem-extension 27 should preferably be of diameter less than that of the stem 26 by an amount at least equal to the intended projection of the spline 18 into the shaft hole, and for the reception of the 100 spline a groove 30 is made along the stem, one end of the groove opening through the shoulder between the stem 26 and extension 27.

Before the core is put in the mold cavity, 105 the sleeve 16 is placed on the stem 26, with the slot 17 radially registering with the groove 30. The spline 18 is then placed in the registering slot and groove, so as to project through the former and rest on the bot- 110

tom of the groove, these pre-formed parts being all dimensioned and shaped for neat interfitting in the stated relation. The upper portion of the spline 18 projects above the level of the liner 16, to be invested by the cast material of the body 11. Specifically the spline may be a steel bar with its ends turned up as at 18^a and with small ears 18^b struck out at the angles of the ends and longitudinal-bar of the spline. Thus the entire upper edge of the bar of the spline, its laterally extending ears 18^b, and its radially extending ends 18^a, may all be invested with the cast metal.

15 When placed in the mold, the parts are in absolutely centered position, with the spline most accurately located and positioned against displacement, so that all that remains to be done for completing the article is to effect the casting operation in usual fashion.

After the casting has been completed the machine-element is removed from the sand, the detachable head of the core pulled off, 25 and the core stem withdrawn from the shaft hole. The external surfaces of the article may be then treated in any way usual with the treatment of castings.

For the production of many classes of machine elements no machining whatever of 30 the product is necessary. In none of them is machining of the shaft hole or spline requisite. The units thus produced are of greatest uniformity and precision in the 35 centering, size and straightness of the shaft holes and in the location, size and extent of projection of the spline. Spline anchorage is absolute.

Of course it will be understood that the 40 shape of the spline may be widely varied, and that contour-changes of the embedded portions of the spline may be made. For one instance, the up-turned ends 18—which, in the present illustration, advantageously 45 coöperate with the thick head-portions of the cast body, might not be at all suitable to some articles, but other anchoring-shapes of spline bar may be employed with accord-

ant change in details of the mold, if need be; and in all such details it will be understood that, while certain features of my invention are claimed in detail for their specific advantages, many changes may be made without departure from the spirit of my invention in its broader aspects, and 55 within the scope of the appended claims.

What I claim is:

1. A splined-machine-element comprising a shaft-receptive liner having a slot, a spline projecting inwardly through said slot and outwardly beyond the liner, and a cast body exteriorly investing said liner and the outwardly-projecting spline portions.

2. A spline-carrying machine-element comprising a liner affording and defining an axial shaft-hole and having an opening therein, a cast body investing said liner, and a pre-formed spline partially embedded in said cast body and extending through said opening in the liner.

3. A splined machine-element comprising a liner defining an axial shaft-hole and having an opening, a cast body investing said liner, and a spline having an axially extending body and outwardly turned ends, said ends embedded in said cast body and said spline extending through said liner-opening.

4. A machine-element comprising in combination a cylindrical liner having a slot, a spline having a longitudinal bar and up-turned ends, said bar extending through said slot and said ends projecting radially therebeyond, and a body cast around said liner and spline-ends.

5. As an article of manufacture, a unitary machine element comprising a cylindrical liner having a slot, a spline of non-circular cross-section arranged longitudinally of said slot with its inner portion projecting inwardly through said slot and its outer portion projecting outwardly beyond the liner, and a cast-metal body exteriorly investing said liner and the outwardly projecting spline portion and uniting them with the body, substantially as specified.

ALVA J. FISHER.
